Primary Examiner — Brett Miller*Assistant Examiner* — Jasmine L. Comedy(74) Attorney, Agent, or Firm — Squire Patton Boggs (US) LLP(57) CLAIM

The ornamental design for a hotel capsule, as shown and described.

DESCRIPTION

FIG. 1 is a front perspective view of a hotel capsule;

FIG. 2 is a front view of the hotel capsule;

FIG. 3 is a rear view of the hotel capsule;

FIG. 4 is a left side view of the hotel capsule;

FIG. 5 is a right side view of the hotel capsule; and,

FIG. 6 is a top view of the hotel capsule.

Broken lines show portions of the hotel capsule that form no part of the claimed design.

1 Claim, 6 Drawing Sheets(56)
